UNITED STATES PATENT OFFICE.

HUDSON MARTIN AND JOEL RUSSEL PALMER, OF ROANOKE, MISSOURI.

COMBINED WHIP AND ROBE LOCK AND LINE-HOLDER.

SPECIFICATION forming part of Letters Patent No. 380,633, dated April 3, 1883.

Application filed December 8, 1887. Serial No. 257,349. (No model.)

To all whom it may concern:

Be it known that we, HUDSON MARTIN and JOEL RUSSEL PALMER, citizens of the United States, residing at Roanoke, in the county of Howard and State of Missouri, have invented 5 certain new and useful Improvements in Buggy-Whip Sockets, of which the following is a description.

Our invention relates to certain new and useful improvements in a combined whip-socket, rein-holder, and robe-lock; and it consists in the novel construction and arrangement of the parts thereof, which will be more fully hereinafter described, and particularly pointed 15 out in the claims.

The object of our invention is to provide a simple and effective combined attachment for vehicles, the parts of which are strong and durable, easily handled, and readily understood and operated, and comparatively inexpensive in manufacture. We attain this object by the construction illustrated in the accompanying drawings, wherein like letters of reference indicate similar parts in the several 25 views, and in which—

Figure 1 is a perspective view of our improved form of combined whip-socket, rein-holder, and robe-lock, shown attached to a dasher-board. Fig. 2 is a transverse vertical 30 section thereof. Fig. 3 is a horizontal section on the line $x-x$ of Fig. 2. Fig. 4 is a detail perspective view of the operating-key for the whip-socket.

A indicates the socket proper, which is 35 formed with a series of apertures, a , of any suitable configuration, for the purposes which will be obviously apparent. The upper part of the socket has a leather ring, a' , inserted therein to prevent the whip-butt from injur- 40 ing the head of the socket. To one side of the upper part of the socket a lug, A', is integrally formed, which is provided with a screw-threaded aperture adapted to be engaged by a screw, S, which is secured at its inner end to a semi- 45 circular spring-plate, which has one of its ends reduced, as at b. Adjacent to the reduced end b of the said semicircular plate B an aperture, a^2 , is formed in the socket, through which the upper end of a chain, C, is secured 50 by the engagement of said reduced end b with one of the links, as shown in Fig. 1. The said chain then passes downward and is secured to

the robe, and thence upward again and permanently attached to a lug, a^3 , integrally formed with the lower side of the socket A.

55

A key, D, is used to operate the screw S and force the semicircular spring-plate inward into the central part of the socket A, or to withdraw the same, as will be readily understood. By forcing the said plate inward the 60 reduced end thereof passes over the aperture a^2 in the upper part of the socket, as shown in Fig. 1, and for the purposes hereinbefore set forth. When said semicircular plate is forced inward, it also has a tendency to lock the whip 65 in the socket by bearing against the butt thereof.

Secured to the upper side of the socket is a corrugated sector-plate E, and above said sector-plate a pawl, F, is pivotally mounted in 70 connection with the socket, and is formed with a corrugated head adjacent to and surrounding its pivotal point. The operating or extended handle of the said pawl is raised and turned back against the dash-board when the 75 reins are placed over the sector-plate E, and the said pawl then turned down, as shown in Fig. 1, and the reins will be securely held against displacement.

The utility and adaptability of our improved 80 device being obviously apparent, it is unnecessary to further enlarge upon the same herein.

We claim—

1. The device herein set forth, comprising a whip-socket having a leather ring in the upper end thereof, the semicircular plate adapted to be propelled inward into the socket and having a reduced end, as set forth, a chain, C, permanently secured at one end to the socket and adapted to be thrown around the robe to 85 lock the same, and then secured at its upper end to the reduced end of the semicircular plate, and the rein-holder on the side of the socket, constructed substantially as described.

2. The combination, with the socket constructed as set forth, of the corrugated sector-plate E, and the pawl F, having a corrugated head, as set forth, the said parts acting conjunctively to lock the reins in connection with the socket, as set forth.

3. The combination, with the whip-socket, of the semicircular plate B, actuated by a screw turned by a key, which has a reduced end, b, the chain F, adapted to be locked by the re-

95

100

duced end of the semicircular plate at its upper end and encircle the robe and be secured to a lug integrally formed with the lower part of the socket, substantially as described.

5 4. The combination, with the whip-socket proper, of the leather ring a' , mounted in the inner upper end thereof, and a semicircular spring-plate, B, mounted below said ring a' and attached to the inner end of a screw, S,

adapted to be operated by a key to project the said plate B into or withdraw it from the internal part of the said socket, substantially as described.

HUDSON MARTIN.
